USPTO Office Action of Sep. 3, 2020 for U.S. Appl. No. 29/653,497.

Primary Examiner — David G Muller

(74) Attorney, Agent, or Firm — Cook Alex Ltd.

(57) **CLAIM**

The ornamental design for a catheter gripping aid, as shown and described.

DESCRIPTION

FIG. 1 is a perspective view of a catheter gripping aid, showing the new design.

FIG. 2 is a top plan view thereof.

FIG. 3 is a bottom plan view thereof.

FIG. 4 is a right side elevational view thereof.

FIG. 5 is a left side elevational view thereof.

FIG. 6 is a rear elevational view thereof; and,

FIG. 7 is a front elevational view thereof.

The broken line showing parts of the drawings is included for the purpose of illustrating use and environment and forms no part of the claimed design.

1 Claim, 3 Drawing Sheets
